Des. 224,705
Patented Sept. 5, 1972

224,705

AUXILIARY WHEEL FOR SNOWMOBILE

Martin L. Mattson, 10 Drake Road,
Duluth, Minn. 55803

Filed July 20, 1971, Ser. No. 164,489

Term of patent 14 years

Int. Cl. D12—16

U.S. Cl. D14—6

Fig 1

Fig 2

Fig 3

FIG. 1 is a perspective view of an auxiliary wheel for a snowmobile embodying my new design.

FIG. 2 is an end view thereof.

FIG. 3 is a side elevational view thereof.

FIG. 4 is an end view opposite to that of FIG. 2.

FIG. 5 is a top plan view.

FIG. 6 is a side elevational view opposite to that of FIG. 3.

FIG. 7 is a bottom plan view thereof.

I claim:

The ornamental design for an auxiliary wheel for a snowmobile, as shown.
